UNITED STATES PATENT OFFICE.

WILLIAM S. HAMM, OF HUBBARD WOODS, ILLINOIS, ASSIGNOR TO THE ADAMS & WEST-
LAKE COMPANY, A CORPORATION OF ILLINOIS.

LAMP.

1,196,947.

Specification of Letters Patent.

Patented Sept. 5, 1916.

Application filed January 29, 1916. Serial No. 75,014.

To all whom it may concern:

Be it known that I, WILLIAM S. HAMM, a citizen of the United States, and resident of Hubbard Woods, county of Cook, and State 5 of Illinois, have invented certain new and useful Improvements in Lamps, of which the following is a specification, and which are illustrated in the accompanying drawings, forming a part thereof.

10 The invention relates to oil-burning lamps of the kind adapted for outdoor use, as on vehicles, and more particularly to lamps of the so-called top draft type in which the air for supporting combustion enters near 15 the top of the lamp casing. In lamps of this type it is found that under the influence of severe jars the flame may be extinguished. This trouble has been developed in using the lamp at the rear ends of auto trucks. In 20 this service when the vehicle wheel drops from an elevation of a few inches the abrupt and severe jar has a tendency to extinguish the lamp, probably due to a reversal of vapor currents which momentarily deprives 25 the flame of oxygen.

The object of this invention is to safeguard the flame against such extinguishing action; and it consists broadly in the provision of means for delivering below and 30 around the burner a supplemental air supply, with means for preventing a too violent air current at this point during high winds, and for retarding any tendency of the air to move in a reverse direction.

35 The details of the invention are fully pointed out herein, and it is illustrated in the accompanying drawings, in which—

Figure 1 is a vertical sectional view of the lamp; Fig. 2 is a horizontal plan section on 40 the line 2—2 of Fig. 1; Fig. 3 is a detail of the lamp font and the air trunk for delivering to the burner the supplemental air supply; Fig. 4 is an inside view of a cap for covering the outer end of the air trunk, and 45 a baffle for fitting within the trunk; Fig. 5 is a side elevation of the lamp, partly broken away, showing a modified form of construction; Fig. 6 is a plan view of the lamp, partly broken away, showing the construc-

tion of Fig. 5; and Fig. 7 is a detail section 50 on the line 7—7 of Fig. 5.

The lamp is usually provided with a metal cylindrical casing 10, having a lateral lens 11 and provided with an exhaust opening 12 and a central conical chimney flue 13. The 55 dome 14 of the lamp is provided with a series of air induction ports 15, and a foraminous screen 16 is interposed between these ports and the combustion chamber. The font is shown at 17 and its burner at 18.

60 So far as thus described the lamp is of known construction. The air enters at the ports 15 and passes down into the combustion chamber, sweeping the walls thereof and feeding the flame at the burner. The products of combustion rise from the burner and 65 pass out through the flue 13 and opening 12.

The improvement in the lamp consists in an air trunk 19, entering through a side wall 70 of the lamp casing and inclosing the burner 18, and being provided in its upper wall with an opening 20 which surrounds the burner. For convenience in manufacture the trunk 75 is made in two portions, its main body portion being attached to the casing wall and being open at its inner end partially inclosing the burner. The other section, 21, of the trunk is in the form of an open-sided box attached to the font and telescopically engaging the main section of the trunk, as 80 shown in Fig. 2, when the font is slid into place in the casing, through a suitably closed opening in the wall thereof.

The outer open end of the trunk 19 is 85 guarded by means of a cap 22, which covers the same, and is attached to the outer face of the lamp casing. This cap is provided at each side with induction ports 23, as numerous as may be found desirable. In order to prevent the air from blowing entirely through the cap from side to side, and 90 thus setting up a suction within the air trunk, a vertical partition 24 is placed within the cap and crosses the mouth of the trunk.

95 To check any tendency of the air to flow outwardly through the trunk 19, a baffle is inserted within the latter and preferably

takes the form of a cone frustum 25. For the purpose of retarding the velocity of the entering air currents the outer end of the trunk is preferably contracted, and, in the 5 preferred form of construction, this is accomplished by applying to the outer end of the trunk a guard 26 in the form of a cone frustum. This contraction of the outer end of the trunk, while preferable, is not essential, and in the modification shown in Figs. 10 5, 6 and 7 it is provided with a flaring mouth 27, and the inclosing cap 28 is shown as circular in form, its ports 29 being in the upper portion thereof and being guarded by 15 an outer shield 30.

While I have shown the preferred form of construction and one modification thereof, other changes may be made without departing from its scope, and I therefore do 20 not desire to be limited to the details as shown.

I claim as my invention—

1. In a lamp, in combination, a casing having at its upper end lateral ports entering its 25 flame chamber for normally supplying air to support combustion, an oil font within the casing, a burner mounted on the font, and an air trunk entering laterally through the side wall of the body and inclosing the wick tube 30 of the burner and having an opening in its upper wall through which the burner projects and a supplemental supply of air is delivered thereto.

2. In a lamp, in combination, a closed 35 casing having lateral air induction ports and an exhaust opening at its upper end, a font within the casing and having a burner, an air trunk entering through the side wall of the casing and inclosing the burner and having 40 a discharge opening adjacent thereto, and a baffle within the trunk for retarding outflow therethrough.

3. In a lamp, in combination, a closed 45 casing having lateral air induction ports and an exhaust opening at its upper end, a font within the casing and having a burner, an air trunk entering through the side wall of the casing and inclosing the burner and having 50 a discharge opening adjacent thereto, and a cap covering the outer end of the trunk and having lateral perforations.

4. In a lamp, in combination, a closed casing having lateral air induction ports and an 55 exhaust opening at its upper end, a font within the casing and having a burner, an air trunk entering through the side wall of the casing and inclosing the burner and having 60 a discharge opening adjacent thereto, a cap covering the outer end of the trunk and having lateral perforations, and a vertical partition in the cap crossing the open end of the trunk.

5. In a lamp, in combination, a closed casing having lateral air induction ports and an

exhaust opening at its upper end, a font 65 within the casing and having a burner, an air trunk entering through the side wall of the casing and inclosing the burner and having 70 a discharge opening adjacent thereto, and a baffle within the trunk in the form of a frustum having its smaller end directed inwardly.

6. In a lamp, in combination, a casing having at its upper end lateral ports entering its flame chamber for normally supplying air 75 to support combustion, an oil font within the casing, a burner mounted on the font, and an air trunk entering laterally through the side wall of the body and inclosing the wick tube of the burner and having an opening in 80 its upper wall through which the burner projects and a supplemental supply of air is delivered thereto, the outer end of the trunk being contracted and projecting beyond the wall of the casing. 85

7. In a lamp, in combination, a closed casing having lateral air induction ports and an exhaust opening at its upper end, a font within the casing and having a burner, an air trunk entering through the side wall of 90 the casing and inclosing the burner and having a discharge opening adjacent thereto, the outer end of the trunk being contracted, a baffle within the trunk in the form of a frustum having its smaller end directed in- 95 wardly, a cap inclosing the outer end of the trunk and having lateral perforations, and a vertical partition in the cap crossing the open end of the trunk.

8. In a lamp, in combination, a closed casing having lateral induction ports at its upper end for normally supplying air to support combustion, a font within the casing and having a burner, an air trunk entering laterally through the casing wall and inclosing the burner and having an upwardly-directed opening surrounding the burner. 100

9. In a lamp, a casing having a side door, a font slideable into service position through such door, an air trunk entering laterally 110 through the casing wall and leading to the burner, the inner end of the trunk being carried by the font and telescopically engaging the main section of the trunk, such trunk having an opening through which the burner 115 projects.

10. In a lamp, a casing having a side door, a font slideable into service position through such door, an air trunk entering laterally 120 through the casing wall and leading to the burner, and a member carried by the font and adapted to form the inner end of the trunk when the font is in service position, such trunk having an opening through which the burner projects. 125

11. In a lamp, in combination, a casing having at its upper end lateral ports entering its flame chamber for normally supply-

ing air to support combustion, an oil font within the casing, a burner mounted on the font, and an air trunk projecting beyond the wall of the casing and being tapered.

5 12. In a lamp, in combination, a casing having at its upper end lateral ports entering its flame chamber for normally supplying

air to support combustion, an oil font within the casing, a burner mounted on the font, an air trunk projecting beyond the wall of the 10 casing and being tapered, and a cap covering the outer end of the trunk and having lateral openings.

WILLIAM S. HAMM.
